(57) **CLAIM**

The ornamental design for a mug as shown and described.

DESCRIPTION

1. Mug

1.1 : Left

1.2 : Top

The mug is cylindrical and continues upwards, with one part of the body wider in diameter than the rest of the body; this width starts approximately in the middle of the body and ends sharply; there is a handle on the side of the mug, shaped like the letter D and hollow on the inside; the narrower part allows the mugs to be stacked.

(Continued)

The broken lines showing a boundary form no part of the claimed design. The faded portions within the boundary line form no part of the claim.
